FOUNTAIN DEVICE

Richard H. Jennings, 1129 Ferdon, Ann Arbor, Mich.
Filed Mar. 1, 1961, Ser. No. 92,639
11 Claims. (Cl. 239—23)

The present invention relates to an apparatus and method for creating fountains, and more particularly to an improved mechanism which is adapted to be submerged in a body of liquid and on energization is effective to create a compound fountain of liquid projecting upwardly from the surface thereof.

The present invention is applicable for creating fountains for both utilitarian and artistic purposes. Conventional systems for creating fountains generally employ an expensive network of piping and an elaborate pumping and filtration system to supply a requisite capacity of clean liquid at the desired pressure to the high pressure sprayheads or nozzles through which a stream of liquid is projected into the air. These conventional fountain systems are characterized by the inherent disadvantage of being inflexible due to the permanency of their installation and their relatively high cost because of the extensive network of high pressure piping required. In addition, the conventional fountain systems employing high-pressure spray nozzles are limited in the variety of fountain configurations that can be obtained, some of which are accompanied by an undesirable and excessive fine spray component or fallout, which is readily carried by air currents beyond the limits of the liquid pool.

It is, accordingly, a primary object of the present invention to provide an improved apparatus and method for creating fountains which is of simple design, which can be simply installed and easily maintained, which is readily adaptable to a variety of different type of liquid pools, and which is readily movable to various locations in a pool providing versatility and flexibility unobtainable in fountain systems heretofore known.

Another object of this invention is to provide an improved fountain apparatus which enables the attainment of a variety of different fountain configurations having dramatic visible and audible kinetic effects unobtainable in fountain systems heretofore known.

Still another object of the present invention is to provide an improved fountain apparatus which can be employed singly or in multiples providing therewith a plurality of compound fountains of similar or varying configuration producing a composite aesthetic or utilitarian effect and which fountain apparatuses can be simply and automatically controlled to provide periodic configuration changes producing therewith a dynamic aesthetic display.

A further object of the present invention is to provide an improved fountain apparatus which is of simple design, of economical construction, of durable operation, and which apparatus concurrently simplifies and reduces the cost and maintenance of the design, construction and maintenance of the liquid pools in which the fountain system is employed.

The foregoing and other objects of this invention are achieved by a fountain apparatus incorporating therein a combined high-pressure spray nozzle and an impeller immersed in a pool of liquid and disposed adjacent the surfaces thereof which is rotated by a submersible motor whereby a compound fountain configuration is created including a substantially solid column of liquid projected upwardly through the spray nozzle and a substantially solid column of liquid projecting above the surface of the body of liquid through the action of the impeller which can be varied in accordance with the speed of rotation of the impeller, the size of the impeller, the configuration of the impeller, the depth of the impeller beneath the surface of the liquid, and the particular configuration and

2

type of guide means employed for encircling the impeller.

Other objects and advantages of the present invention will become apparent from the following detailed description taken in conjunction with the accompanying drawings, wherein:

FIGURE 1 is a perspective view of a fountain apparatus constructed in accordance with one of the embodiments of the present invention and generally illustrating the relationship between the submersible impeller and spray nozzle supported on a suitable supporting framework;

FIG. 2 is a plan view of an impeller employed in the fountain apparatus shown in FIGURE 1;

FIG. 3 is a fragmentary side elevation view of the impeller shown in FIG. 2 and mounted on a rotatable drive shaft;

FIG. 4 is a fragmentary plan view of the fountain apparatus shown in FIGURE 1 and illustrating in particular the axial alignment of the spray nozzles and impeller thereon;

FIG. 5 is a fragmentary transverse vertical sectional view of an alternate embodiment of a fountain apparatus of the type shown in FIGURE 1 utilizing a hollow drive shaft as the spray nozzle;

FIG. 6 is a fragmentary transverse vertical sectional view of a fountain apparatus of the type shown in FIGURE 1 illustrating another alternate satisfactory modification thereof;

FIG. 7 is a fragmentary side elevation view partly in section of still another alternate satisfactory modification of the fountain apparatus shown in FIGURE 1 employing a main pump at the base thereof for ejecting a stream of liquid upwardly through a tubular central shaft;

FIGS. 8 to 12 are schematic vertical sectional views illustrating the installation of a fountain apparatus of a type shown in FIGURE 1 in a variety of pools of different configuration;

FIGS. 13 and 14 illustrate two typical fountain configurations which are obtainable with the fountain apparatus comprising the present invention;

FIG. 15 is a schematic plan view of a liquid pool incorporating therein four fountain apparatus providing multiple fountain effects; and

FIG. 16 is a schematic wiring diagram of a control circuit for automatically and sequentially controlling the operation of the fountain apparatuses installed in the pool as shown in FIG. 15.

Referring now in detail to the drawings and as may be best seen in FIGURES 1 to 3, a fountain apparatus 20 constructed in accordance with one embodiment of this invention is comprised of a tripod supporting frame 22 including three adjustable telescoping legs 24 which are securely fastened to a central housing sleeve 26. A variable speed motor 28 is slidably disposed in the central housing sleeve 26 and is securely fastened therein by means of a series of set screws 30. The motor 28 may comprise an electrical motor which is provided with a liquid tight housing enabling the motor to be submerged in a pool of liquid, such as water, for example. Alternatively, the motor 28 may comprise a fluid drive unit such as a hydraulic motor, for example, which receives a supply of pressurized hydraulic fluid through suitable conduit means extending through the pool of liquid and connected to a central supply pump located adjacent to the pool. When the motor 28 comprises an electric motor, the electric power thereto can be supplied through a suitable water-tight insulated conductor 32 which is electrically connected to the motor and extends beneath the surface of the pool to a central power source which may be disposed conveniently at the edge of the pool.

In the exemplary embodiment of the fountain apparatus shown in FIGURE 1, a shaft 34 of the motor 28 is pro-

vided with an impeller assembly 36 comprising an impeller blade 38 and a hub 40 which is securely fastened to the end of the shaft 34. The impeller blade 38 includes upturned portions 42 as may be best seen in FIG. 3, which are disposed along the trailing edge thereof and which serve to deflect the water upwardly as the impeller blade 38 is rotated at high speed. The angularity of the upturned portions 42 can be varied depending on the specific fountain configuration desired.

During operation, the impeller blade 38 is disposed beneath the surface of the liquid and the rapid rotation thereof by the motor 28, raises a substantially solid column of water above the surface of a pool. It has been observed that as the depth of the impeller beneath the surface of the pool increases, the substantially solid column of water rising above the surface of the pool, becomes more precise and less divergent. This characteristic is attributed to the belief that the water surrounding the upwardly traveling column of water before it projects above the surface of a pool, is relatively stagnant and serves as a directional guide or shield which improves the vertical orientation of the rising column of liquid with respect to the axis of rotation of the impeller assembly 36.

This shielding or guiding effect of the liquid surrounding the upwardly rising column of liquid, can be supplemented, if desired, by a mechanical guide means such as a duct 44 as shown in FIGURE 1, which encircles the impeller blade 38 and is disposed in substantial axial alignment with the axis rotation thereof. The duct 44 can be suitably mounted on a series of radially extending support members 46 which extend upwardly and outwardly from the housing sleeve 26, to which they are securely fastened. The duct 44 is preferably of a venturi configuration to facilitate entry of the liquid from beneath the duct and upwardly therethrough in response to rotation of the impeller blade 38. While a venturi-shaped duct comprises a preferred embodiment of this invention, it will also be appreciated that satisfactory operation has also been achieved by employing ducts of a general cylindrical and conical configuration. The use of mechanical guide means such as cylindrical ducts, conical ducts, or the venturi duct 44 as shown in FIGURE 1 increases the efficiency of the impeller blade 38 by minimizing tip losses and accordingly increases the height of the column of liquid obtainable for a given impeller design and speed of rotation.

Further increases in the efficiency of the impeller and height of the column of liquid projected by the impeller assembly 36, can be achieved by incorporating a series of vanes 48, as shown in FIG. 5, extending radially inwardly from the inner surface of the duct 44 which coat with the rising column of liquid moving upwardly therethrough and provide for a reduction in the centrifugal or spiral component thereof thereby reducing the divergence of the column of liquid above the surface of the pool. The inclusion of the vanes 48 in the duct 44 also reduces the diameter of the return pattern of the column of liquid on the surface of the pool. As shown in FIG. 5, the vanes 48 may terminate at a point corresponding to the upper end of the duct 44 or may extend upwardly therefrom as the vanes 48a shown in FIG. 7. Regardless of the specific type of vanes, if any, employed, the upper edge of the duct 44 is disposed substantially at or below the surface of the liquid in the pool. Accordingly, the upper portions of the vanes 48a project above the surface of the pool.

In addition to the impeller assembly 36 for raising a substantially solid column of liquid upwardly from the surface of the pool, the fountain apparatus 20 also includes at least one spray jet or nozzle 50 through which a pressured stream of liquid is projected upwardly above the surface of a liquid pool. In the exemplary fountain apparatus shown in FIGURE 1, three nozzles 50 are employed which extend upwardly and inwardly in a manner

as may be best seen in FIGS. 1 and 4 having the lower end portions thereof affixed to and in communication with a distributor ring 52 extending around and supported by the upper edge of the duct 44. The distributor ring 52 is provided with a depending conduit 54 to which a suitable flexible tube or other piping 56 is connected for supplying the requisite capacity of a liquid at the desired pressure to the distributor ring 52 and the nozzles 50 mounted thereon. The end of the distributor ring 52 as shown in FIG. 4, is provided with a removable plug 58 which can be quickly removed for cleaning the interior of the distributor ring. The sloping configuration of the nozzles 50 as shown in FIGURE 1 is preferred in that the resultant configuration does not interfere with the upwardly rising column of water moving upwardly through the duct 44 in response to the rotation of the impeller blade 38. Accordingly, the substantially solid characteristics of the water column raised by the impeller are not disturbed by the nozzles 50.

An alternate satisfactory method of providing a pressurized column of liquid extending upwardly and substantially axially of the fountain created by the impeller is illustrated in the fountain apparatus 20a shown in FIG. 5 wherein a tubular shaft 60 is employed in lieu of the nozzles 50. The basic features of the fountain apparatus 20a are similar to those heretofore described in connection with the fountain apparatus 20 shown in FIGURE 1 and includes an impeller 38 mounted to rotate within a duct 44 having vanes 48 therealong for raising a substantially solid column of liquid above the surface of the pool. The upper portion of the motor 28 as shown in FIG. 5 is provided with a streamlined housing 62 including an inner chamber 64 which is connected to an inlet tube 66 for supplying the requisite quantity of pressurized liquid. The tubular shaft 60 is rotatably journaled in a pair of bearings 68 which are supported by the streamlined housing 62 and the shaft is rotatably sealed by means of a disc seal 70 encircling the lower portion of the shaft adjacent to the lower bearing 68 as viewed in FIG. 5.

Rotation of the tubular shaft 60 is achieved by the motor shaft 34 including a coupling 72 thereon fastened to the lower portion of the tubular shaft 60 for transmitting rotational torque thereto. The impeller 38 is affixed to the projecting end portion of the tubular shaft 60 and adjacent to the end of streamlined housing 62. The upper end portion of the tubular shaft 60 extends upwardly beyond the upper edge of the duct 44 and above the high water mark of the liquid pool to prevent interference between the liquid in the pool and the high-pressure stream ejecting therefrom.

In the exemplary fountain apparatus shown in FIGURES 1 and 5, the liquid for creating the pressurized fountain of liquid ejected from the nozzle is supplied to the apparatus by means of suitable piping or conduits 56 which are connected to a principal liquid supply system or a suitable central pumping station. Two alternate embodiments of the fountain apparatus are shown in FIGS. 6 and 7 which comprise units having a self-contained pumping circuit for supplying pressurized fluid to the nozzle of the fountain apparatus.

As shown in FIG. 6, the fountain apparatus 20b includes a streamlined housing 62b including an inner chamber 64b including an inlet tube 66b disposed in communication therewith which may be provided with a suitable screen or strainer (not shown) for filtering the liquid entering the inner chamber 64b. The liquid in the inner chamber 64b is drawn upwardly through an annular port 74 and into a pump body 76 from which it is pumped outwardly through one or more tubular nozzles 50b extending upwardly above the duct 44 in a manner as shown in FIG. 6. The pump can be of a centrifugal vane-type, for example, including a series of radially extending vanes 78 which are adapted to be rotated at high speed so as to force the liquid by centrifugal action under the requisite pressure outwardly and upwardly through the nozzles 50b.

The radial vanes 78 are affixed to an extension shaft 80 which is connected to the motor shaft 34 and rotatably driven thereby. The extension shaft 80 is rotatably journaled in a pair of axially spaced bearings 82 and projects upwardly beyond the streamlined housing 62b to which the impeller blade assembly 36 is fixedly secured. The extension shaft 80 adjacent to the lower bearing 82 is sealed by means of a resilient seal 84 preventing leakage upwardly through the housing.

In accordance with the construction shown in FIG. 6, rotation of the motor 28 causes concurrent pumping and discharge of liquid through the nozzles 50b and ejection of a column of liquid upwardly through the duct 44 through the rotation of the impeller blade 38. To enable relative variation of the fountain created by the impeller and the pressurized stream discharged from the nozzles 50b, the inlet tube 66b may be provided with a suitable inlet valve 86 which is manually or remotely adjustable, such as by a solenoid, for example, to enable variation of the inlet flow of liquid into the pump body 76 for any given speed of rotation of the extension shaft 80.

An alternate exemplary construction of a self-contained fountain apparatus 20c is illustrated in FIG. 7 wherein the pump body 76a is mounted adjacent to the base of the motor 28 and is drivingly connected to the lower projecting end portion of a tubular motor shaft 88. A series of radial vanes 78a are affixed to the tubular motor shaft 88 and are effective to transmit pressurized fluid entering the pump body through an inlet valve 86a through a transmission bore 90 in the pump body housing and thence through a series of apertures 92 in the tubular motor shaft 88 which communicate with a longitudinal bore 93 extending upwardly through the tubular motor shaft 88. The pressurized liquid is finally discharged out the upper projecting end of the shaft 88.

The construction of the fountain apparatus 20c as shown in FIG. 7 provides an advantage over the fountain apparatus 20b shown in FIG. 6 by reducing the congestion immediately below and adjacent to the impeller 38 avoiding restriction of liquid flow upwardly through the duct 44. The inlet valve 86a to the pump body 76a can also be remotely or manually adjustable to provide the desired flow rate of liquid out of the tubular motor shaft 88 for a given r.p.m. to achieve the desired configuration of the pressurized stream or upstanding fountain in relationship to the upwardly rising column of liquid or base fountain ejected through the duct 44 by the impeller blade 38.

In accordance with the fountain apparatuses hereinbefore shown and described, a variety of different fountain configurations can be created dependent upon the specific configuration of the pressurized column of liquid and the specific configuration of the substantially solid column of liquid directed upwardly by the rotation of the impeller. The particular configuration of the column of liquid or base fountain projected upwardly by the impeller is primarily dependent upon the following variables: the size, configuration and pitch of the impeller blade; the depth of the impeller blade beneath the surface of the liquid pool; the speed of rotation of the impeller blade expressed in terms of revolutions per minute or in tip speed in feet per second; and the type of duct means employed for encircling the impeller which may include a series of radially projecting vanes for reducing the spiraling motion of the rising column. On the other hand, the specific configuration and height of the pressurized stream of liquid or upstanding fountain directed upwardly through the nozzle of the fountain apparatus is dependent upon the pressure and rate of flow of liquid ejected; the number of nozzles employed and their relative angularity relative to the axis of rotation of the impeller; and the relative angularity of a multiple nozzle fountain apparatus relative to each other. The extreme flexibility provided by the fountain apparatuses comprising the present invention make them ideally suitable for both utilitarian and aesthetic purposes including aeration, cooling, and

decorative displays, for example. The rotary action of the impeller additionally serves to disintegrate any flotsam floating on the surface of the liquid which constitutes still another advantage of the present invention.

The extreme flexibility provided by the units enables their placement in any one of a variety of pools, typical examples of which are schematically illustrated in FIGS. 8 to 12. The pool installation shown in FIG. 8 is typical of a conventional pool wherein the fountain apparatus 20 can be placed at any convenient location on the floor of the pool 94 and the telescoping legs thereof can be appropriately adjusted so as to position the impeller blade at the appropriate depth beneath the surface of the liquid. In the specific installation shown in FIG. 8, the motor of the fountain apparatus 20 is of the hydraulic type which is driven by hydraulic fluid transmitted thereto by submerged piping 96 extending beneath the surface of the pool and connected to a submerged manifold 98. The use of a submerged manifold is particularly applicable to installations wherein a plurality of fountain apparatuses are employed to create combined utilitarian or aesthetic effects. Suitable hydraulic fluid in the desired quantity and at the requisite pressure is supplied to the submerged manifold 98 by means of a conduit 100 connected to a hydraulic supply unit 102 which can be conveniently located at the edge of the pool. In fountain apparatuses of the type which are not self-contained but rely on an outside pressurized liquid source for supplying liquid in the requisite quantity and pressure to the spray nozzle thereof, a suitable liquid manifold similar to the submerged manifold 98 can be employed having flexible tubes extending therefrom and connected to the inlet tubes 54 and 66 of the apparatuses shown in FIGURES 1 and 5, respectively.

In addition to the conventional pool shown in FIG. 8, a shallow pool 104, as shown in FIG. 9, can also be provided with a fountain apparatus 20 wherein the pool is provided with a central sump portion 106 in which the fountain apparatus is disposed. A shallow pool 108 is illustrated in FIG. 10 having a substantially constant depth which is insufficient to completely submerge a fountain apparatus of the type shown in FIGURE 1. To achieve satisfactory operation in such a shallow pool, a modified version of the fountain apparatus 20 is employed which utilizes a right angle drive mechanism of a type well known in the art which substantially reduces the overall height of the unit enabling complete submersion thereof beneath the surface of the pool. The modified fountain apparatus which is generally indicated at 110 is provided with adjustable legs similar to the telescoping legs 24 of the unit shown in FIGURE 1 enabling vertical adjustment thereof so as to dispose the impeller at the appropriate depth beneath the surface of the pool.

Still another typical installation is shown in FIG. 11 wherein a relatively deep pool 112 is provided with a caisson 114 submerged in the pool and providing a waterproof housing for a conventional motor 116 which is mounted therein and supported thereby. The installation shown in FIG. 11 is particularly satisfactory for use with relatively high horsepower motors and large diameter impellers in relatively deep pools. The motor drive shaft extends upwardly through a watertight bearing 118 in the upper surface of the caisson 114 and to the projecting shank portion of which the impeller blade assembly 20 is affixed.

Another illustration of a fountain apparatus is illustrated in FIG. 12 wherein the unit is buoyantly supported by a suitable float 120 for maintaining the impeller and nozzle thereof in appropriate position relative to the surface of the body of water. The installation as shown in FIG. 12 is particularly applicable to deep pools and relatively deep bodies of waters such as lakes, streams, bays and the like having deep and irregular bottoms making it difficult to accurately position the impeller relative to the surface of the liquid and to adequately

support the unit. In electrically driven self-contained fountain apparatuses, the float 120 can be suitably anchored to the bottom by a suitable line 122 and electrical energy supplied to the motor thereof by a conductor extending beneath the surface of the body of water to a power source on the shore of the body of water. In units relying on a separate pressure source for supplying liquid to the spray nozzle and for units which are provided with hydraulically driven motors, the appropriate liquids in the quantities and requisite pressures can be satisfactorily supplied to the unit through flexible conduits extending along the bottom of the body of water and connected to pressurized supply sources on the edge thereof.

In accordance with the fountain apparatuses hereinbefore described, a variety of fountain configurations can be achieved which have a particular aesthetic appeal or which may provide optimum cooling or aeration of a liquid in which the fountain apparatus is submerged. Two typical compound fountain configurations obtainable by the fountain apparatus comprising the present invention are illustrated in FIGS. 13 and 14 and comprise a base fountain 124 created by the rotation of the impeller blade of the apparatus and a centrally disposed upright central column or upstanding fountain 126 created by the discharge of the pressurized liquid through the spray nozzles. The specific configuration of the base fountain 124 can be varied by modifying the depth of the impeller blade beneath the surface of the liquid, the size, configuration, and speed of rotation of the impeller blade; and the specific type of ducting encircling the impeller blade. By selecting the appropriate conditions for each of the above variables, base fountain configurations can be produced having a ratio of height to the diameter of the upward moving column of water taken at the surface which ranges from about 3:1 up to about 10:1 and a width ratio comprising the ratio of the fallout or return pattern of the liquid on the surface of the pool to the diameter of the upward moving column of water taken at the surface thereof ranging from about 3:1 up to about 15:1. Each of the base fountains having configurations within the above mentioned ratios are characterized as having a substantially solid column of water emerging from the surface of the pool of liquid and which column is substantially devoid of fragmentation or droplets until the column attains the upper trajectory thereof. The base fountain is further characterized as having a so-called conical hollow inner portion which is disposed in substantial axial alignment with the axis of rotation of the impeller blade and through which conical cavity, the upstanding fountain of pressurized liquid is ejected.

The relatively height of the upstanding fountain 126 is proportional to the pressure employed and can be varied to produce the desired utilitarian and aesthetic effects. In addition, the upstanding fountain 126 may be comprised of a single seemingly unitary column such as shown in FIG. 13 which may comprise a column ejected from a single centrally disposed nozzle or a plurality of smaller nozzles of the type such as shown in FIGURE 1 which converge together and form a single unitary upwardly moving column of liquid. An alternate configuration of the upstanding fountain is illustrated in FIG. 14 wherein the fountain 126a comprises a plurality of individual streams which are adapted to converge at a point spaced above the upper trajectory of the base fountain 124 forming therewith alternate aesthetic effects.

In addition to the variations obtainable in the configuration of the base fountain and upstanding fountain, the specific changes in fountain configuration are also accompanied by changes in audible kinetic effects which provide dramatic changes in the audible effects of the returning water as it strikes the surface of the pool. By the use of a suitable control system, the speed of rotation of the impeller, and the pressure of the liquid supplied to the spray nozzle can be varied and controlled so as to achieve

the desired fountain configuration. In addition to the composite configuration produced by the base fountain and the upstanding fountain, each of the fountains can also be employed independently of the other to achieve a multiple variation in fountain configuration. In addition to the variations obtainable in one fountain apparatus, multiple aesthetic or utilitarian aeration effects can be achieved by automatically controlling the sequential independent or collective operation of a plurality of fountain apparatuses.

A typical arrangement of four fountain apparatuses submerged in a pool is schematically shown in FIG. 15. A kidney-shaped pool 128 is illustrated in the drawing having four fountain apparatuses submerged therein each of which is connected to a central control panel 130 disposed adjacent to the edge of the pool 128. Each of the fountain apparatuses is provided with a variable speed electrical motor which is electrically connected to the central control panel 130 in accordance with a wiring diagram as shown in FIG. 16. The system shown illustrates one exemplary method of providing automatic, controlled sequential independent and collective operation of the units on a time sequence basis to achieve any desired sequence of conversion of the configuration of each of the fountains with respect to each other. It will, of course, be appreciated that any number of fountain apparatuses can be coordinated in accordance with the arrangement and control system shown in FIGS. 15 and 16 to provide for selective automatic group and individual unit sequencing thereby achieving a multitude of variations in operating sequences and fountain configurations. In addition, the portable characteristics of each of the fountain apparatuses enables the simple inclusion or removal of one or more additional units from the pool or their relocation therein providing an extremely high degree of versatility and flexibility.

In the schematic control diagram shown in FIG. 16, each of the four fountain units are automatically controlled on a time sequence basis by varying the quantity of direct current supplied to each of their respective variable electric speed motors. The control system as illustrated comprises a direct current source 132 having connected thereto in parallel an electric timer 134, which is presettable to periodically energize an electric servo motor 136 which rotates wiper contacts 138 mounted on a suitable shaft extending through the variable rheostats 140 which are connected in series in the conductors supplying each of the electric motors 28 of the fountain apparatuses. The particular orientation of each of the wiper contacts 138 with respect to their respective variable rheostat 140 establishes the appropriate operating sequence through which the base fountain of each of the fountain apparatuses will undergo.

The variable rheostats 140 can also be employed for controlling a solenoid valve 142 in each of the conduits 144 supplying a pressurized liquid to the spray nozzles of each of the fountain apparatuses. Accordingly, the timed variation of the variable rheostat setting as determined by the wiper contacts 138 serve to concurrently vary the height of the upstanding fountain in accordance with the variation in pressure of the liquid supplied thereto and also the particular configuration of the base fountain as effected by the speed of rotation of the impeller blade.

While it will be apparent that the preferred embodiments of the invention disclosed are well calculated to fulfill the objects above stated, it will be appreciated that the invention is susceptible to modification, variation, and change without departing from the proper scope or fair meaning of the subjoined claims.

70 What is claimed is:

1. In an apparatus for creating a compound fountain including a base fountain and an upstanding fountain, the combination comprising impeller means adapted to be immersed in a liquid and disposed adjacent to the surface thereof, said impeller means including a plurality of blades thereon having at least a portion thereof angularly

pitched relative to the plane of rotation of said impeller means and adapted to deflect the liquid upwardly in a substantially solid sheet above the surface of the liquid in response to rotation of said impeller means, guide means encircling said impeller means and formed with an opening in the base and top thereof for directing the flow of liquid upwardly toward the surface of the liquid, nozzle means projecting above the surface of the liquid in a position above said impeller means for discharging a substantially solid stream of liquid therefrom, submersible motor means for rotating said impeller means, conduit means disposed in communication with said nozzle means for supplying a pressurized liquid thereto, and supporting means for maintaining said impeller means and said nozzle means in appropriate position relative to the surface of the body of liquid.

2. In an apparatus for creating a compound fountain including a base fountain and an upstanding fountain, the combination comprising impeller means adapted to be immersed in a liquid and disposed adjacent to the surface thereof, shaft means for rotating said impeller means about an axis substantially perpendicular to the surface of the liquid, said impeller means including a plurality of blades thereon having at least a portion thereof angularly pitched relative to the plane of rotation of said impeller means and adapted to deflect the liquid upwardly in a substantially solid sheet above the surface of the liquid in response to rotation of said impeller means, nozzle means projecting above the surface of the liquid for ejecting an upstanding substantially solid column of liquid in substantial axial alignment with said shaft means, submersible motor means for rotating said shaft means, conduit means disposed in communication with said nozzle means for supplying a pressurized liquid thereto, and supporting means for mounting said impeller means and said nozzle means in appropriate position relative to the surface of the body of liquid.

3. In an apparatus for creating a compound fountain including a base fountain and an upstanding fountain, the combination comprising impeller means adapted to be immersed in a liquid and disposed adjacent to the surface thereof, said impeller means including a plurality of blades thereon having at least a portion thereof angularly pitched relative to the plane of rotation of said impeller means and adapted to deflect the liquid upwardly in a substantially solid sheet above the surface of the liquid in response to rotation of said impeller means, guide means comprising a substantially cylindrical shroud encircling said impeller means and disposed contiguous to the tips of the blades thereof for directing the flow of liquid upwardly toward the surface of the liquid, nozzle means projecting above the surface of the liquid for ejecting an upstanding column of liquid in substantially axial alignment with said guide means, submersible motor means for rotating said impeller means, conduit means disposed in communication with said nozzle means for supplying a pressurized liquid thereto, and supporting means for maintaining said impeller means and said nozzle means in appropriate position relative to the surface of a body of liquid.

4. In an apparatus for creating a compound fountain including a base fountain and an upstanding fountain, the combination comprising impeller means adapted to be immersed in a liquid and disposed adjacent to the surface thereof, tubular shaft means for rotating said impeller means about an axis substantially perpendicular to the surface of the liquid, said shaft means projecting above the surface of the liquid forming therewith nozzle means, conduit means disposed in communication with said tubular shaft means for supplying a pressurized liquid thereto, submersible motor means for rotating said shaft means, and supporting means for maintaining said impeller means and said tubular shaft means in appropriate position relative to the surface of the body of liquid.

5. In an apparatus for creating a compound fountain including a base fountain and an upstanding fountain, the

combination comprising impeller means adapted to be immersed in a liquid and disposed adjacent to the surface thereof, said impeller means including a plurality of blades thereon having at least a portion thereof angularly pitched relative to the plane of rotation of said impeller means and adapted to deflect the liquid upwardly in a substantially solid sheet above the surface of the liquid in response to rotation of said impeller means, nozzle means projecting above the surface of the liquid at a position above said impeller means, submersible motor means for rotating said impeller means, pumping means for discharging a substantially solid column of liquid therefrom drivingly connected to said motor means including conduit means disposed in communication with said nozzle means for supplying a pressurized liquid thereto, and supporting means for maintaining said impeller means and said nozzle means in appropriate position relative to the surface of the body of liquid.

6. In an apparatus for creating a compound fountain including a base fountain and an upstanding fountain, the combination comprising impeller means adapted to be immersed in a liquid and disposed adjacent to the surface thereof, tubular shaft means for rotating said impeller means about an axis substantially perpendicular to the surface of the liquid, the upper end of said tubular shaft means projecting above the surface of the liquid forming therewith a nozzle means, submersible motor means for rotating said shaft means, pump means drivingly connected to said submersible motor means including conduit means disposed in communication with said tubular shaft means for supplying a pressurized liquid thereto, and supporting means for maintaining said impeller means and said tubular shaft means in appropriate position relative to the surface of the body of liquid.

7. In an apparatus for creating a compound fountain including a base fountain and an upstanding fountain, the combination comprising impeller means adapted to be immersed in a liquid and disposed adjacent to the surface thereof, nozzle means projecting above the surface of the liquid at a position above said impeller means, submersible variable speed hydraulic motor means for rotating said impeller means, conduit means disposed in communication with said nozzle means for supplying a pressurized liquid thereto, supporting means for maintaining said impeller means and said nozzle means in appropriate position relative to the surface of the body of liquid, and supply means including submersible pipe means for supplying a pressurized fluid to said hydraulic motor means for causing rotation thereof.

8. In an apparatus for creating a compound fountain including a base fountain and an upstanding fountain, the combination comprising impeller means adapted to be immersed in a liquid and disposed adjacent to the surface thereof, said impeller means including a plurality of blades thereon having at least a portion thereof angularly pitched relative to the plane of rotation of said impeller means and adapted to deflect the liquid upwardly in a substantially solid sheet above the surface of the liquid in response to rotation of said impeller means, guide means encircling said impeller means and formed with an opening in the base and top thereof for directing the flow of liquid upwardly toward the surface of the liquid, nozzle means projecting above the surface of the liquid at a position above said impeller means, submersible motor means for rotating said impeller means, conduit means disposed in communication with said nozzle means for supplying a pressurized liquid thereto, a buoyant body disposed in floating relationship on the surface of the body liquid, means for connecting said buoyant body to said motor means for supporting said apparatus and maintaining said impeller means and said nozzle means in appropriate position relative to the surface of the body of liquid, and mooring means for anchoring said apparatus in the body of liquid.

9. In an apparatus for creating a plurality of compound fountains each including a base fountain and an upstand-

11

ing fountain, the combination comprising a plurality of fountain units adapted to be submerged in a body of liquid and disposed at spaced intervals therein, each of said fountain units comprising impeller means immersed in the liquid and disposed adjacent to the surface thereof, said impeller means including a plurality of blades thereon having at least a portion thereof angularly pitched relative to the plane of rotation of said impeller means and adapted to deflect the liquid upwardly in a substantially solid sheet above the surface of the liquid in response to rotation of said impeller means, guide means encircling said impeller means and formed with an opening in the base and top thereof for directing the flow of liquid upwardly toward the surface of the liquid, nozzle means projecting above the surface of the liquid at a position above said impeller means, submersible motor means for rotating said impeller means for discharging a substantially solid column of liquid therefrom, conduit means disposed in communication with said nozzle means for supplying a pressurized liquid thereto, and supporting means for maintaining said impeller means and said nozzle means in appropriate position relative to the surface of the body of liquid.

10. In an apparatus for creating a plurality of compound fountains each including a base fountain and an upstanding fountain, the combination comprising a plurality of fountain units adapted to be submerged in a body of liquid and disposed at spaced intervals therein, each of said fountain units comprising impeller means immersed in the liquid and disposed adjacent to the surface thereof, nozzle means projecting above the surface of the liquid at a position above said impeller means, variable speed submersible motor means for rotating said impeller means, conduit means disposed in communication with said nozzle means for supplying a pressurized liquid thereto, supporting means for maintaining said impeller means and said nozzle means in appropriate position relative to the surface of the body of liquid, and

12

control means including valve means for independently controlling the speed of rotation of said motor means and the pressure of the liquid supplied to said nozzle means of each of said fountain units.

11. The method of creating a decorative fountain display by raising a plurality of compound fountains above the surface of a larger body of liquid comprising the steps of submerging a plurality of fountain units at spaced intervals in the body of liquid, each of said plurality of fountain units comprising submersible variable speed motor means including an impeller thereon disposed below and adjacent to the surface of the body of liquid and rotatable about an axis substantially perpendicular thereto, positioning a nozzle in the body of liquid having the end thereof projecting above the surface of the liquid at a position above said impeller, energizing each of said motor means to rotate each of said impellers and raise a plurality of substantially solid columns of liquid above the surface of the body of liquid forming therewith a plurality of base fountains, discharging a pressurized stream of liquid upwardly from each of said nozzles forming therewith a plurality of upstanding fountains each disposed in substantial axial alignment with respective ones of said base fountains, and independently controlling the speed of rotation of each of said motor means and the pressure of liquid supplied to each of said nozzles for automatically and sequentially varying the configuration of each of said base fountains and each of said upstanding fountains.
